UNITED STATES PATENT OFFICE.

JOHN DARBY, OF SUMMIT, NEW JERSEY, ASSIGNOR TO FRANCIS B. GRIFFIN, OF NEW YORK, N. Y.

MOTION-PICTURE MACHINE.

1,346,880.

Specification of Letters Patent. Patented July 20, 1920.

Application filed March 16, 1916. Serial No. 84,510.

To all whom it may concern:

Be it known that I, JOHN DARBY, a citizen of the United States, and a resident of Summit, in the county of Union and State of New Jersey, have invented certain new and useful Improvements in Motion-Picture Machines, of which the following is a specification.

The invention relates to motion picture projecting machines, and more particularly to devices in such machines for handling and controlling the film strip and to devices and mechanisms coöperating therewith.

Objects of the invention will be set forth hereinafter in part and in part will be obvious herefrom, such objects being realized or attained through the instrumentalities and combinations pointed out in the appended claims.

The invention consists in the novel parts, constructions, arrangements, combinations and improvements herein shown and described.

The accompanying drawings, referred to herein and forming a part hereof, illustrate one embodiment of the invention, and taken in connection with the description serve to illustrate the principles thereof.

Of the drawings:

Figure 1 is a side elevation of a machine constructed in accordance with the principles of the invention, and showing the mechanism in the position in which a film strip is threaded through the machine, and the reserve loops are established;

Fig. 2 is a view corresponding to Fig. 1, but showing the parts in the position in which the film is being run during the projection of the pictures;

Fig. 3 is an elevation looking at Figs. 1 and 2 from the left, with the film strip omitted;

Fig. 4 is a fragmentary elevation, on an enlarged scale, and with parts in section of the slidable loop-establishing devices shown in the upper left hand part of Figs. 1 and 2; and

Fig. 5 is a fragmentary detail, on an enlarged scale, with parts in section and with parts broken away, of the bottom slidable loop-establishing devices shown in the lower parts of Figs. 1 and 2.

The invention comprises sliding or reciprocable means for establishing a reserve loop of the film strip of requisite or predetermined length between the continuously

running reel which carries the supply roll of the film strip and the intermittently feeding portion of the film strip which is co-operating with the projection apparatus proper to project the pictures. In accordance with one feature of the invention, there are provided reciprocable or slidable devices which so establish or determine the reserve loop in the film strip, and also coöperate with and constitute a part of the film strip feeding devices during the operation of the machine.

The preferred embodiment of the invention is illustrated, by way of example, in the accompanying drawings wherein the machine is mounted upon a suitable frame, said frame comprising a vertical portion 1 having the transversely projecting portion 2 at the rear, this portion carrying certain parts of the projecting apparatus proper, and having a base 3 upon which the machine stands.

A tube 4 supported by and extending forwardly from the frame portion 2, carries the projecting lenses in a suitable manner. At its rear end, and mounted on frame portion 2 are the devices for holding or clamping the film strip, which devices may be the same as those shown in my Patent No. 1,280,676. At the forward end of the tube 4 is a rotary shutter 5, carried upon shaft 6, which shaft is rotated through suitable connections in proper time relation with the film strip feeding devices.

In the embodied form of the invention, the film strip is supplied from a continuously unwound roll and is rewound upon another continuously winding roll, and between these rolls it is given a step by step or intermittent feed past the projecting devices proper, the sliding or reciprocable reserve loop-establishing device acting also to establish and preserve a reserve loop of just the proper length between the supplying means and the intermittent feeding means and also between the intermittent feeding means and the rewinding means. As embodied, film strip α is in a roll on reel 7, which reel is rotatable upon a support 8, the reel having, if desired, a clip 9 for holding the end of the film strip. The reel 7 is maintained upon its bearing or support 8 in a suitable manner, as by a latch 10, which latch permits the reel to be slipped on, and is then turned to hold the reel in position, as

shown in Fig. 3. A spring 11 may act against the other side of the reel 7 to hold it against the latch 10 and to serve as a gentle friction brake or drag. The support or shaft 8 is fixed to, or formed with, an upright support 12 carried upon the machine frame and which may be vertically adjustable if desired.

Suitable mechanism is provided for continuously 10 unwinding the film strip α from the reel 7, the embodied form thereof comprising a continuously driven sprocket roller 13, carried upon a shaft 15. The shaft 15 has a pinion 16, meshing with a gear wheel 17. The gear wheel 17 is fixed on a shaft 18, the shaft 18 having a driving crank 19. The sprocket teeth upon roller 13 engage with the sprocket holes in the edges of the film to feed the film strip along. Coöperating 20 with the sprocket roll 13 is one or more spring-pressed rollers 20, carried upon arms 21, which arms are mounted upon a shaft 22. The hub of arm 21 is provided with a cam 23 acted upon by a spring 24 to keep the roller 20 in engagement with the sprocket roll 13 during the feeding of the film, to keep the film strip on the sprocket roller teeth, the roller 20 being grooved circumferentially for this purpose.

30 The slideable or reciprocable reserve loop-establishing means also, in accordance with one feature of the invention, is united and coöperates with certain of the film feeding and directing devices to maintain or pre-serve the reserve loop during the running of the film strip. As embodied, in the frame portion 2 of the machine, a vertically disposed aperture is provided, within which a rod 30 is longitudinally reciprocable, (Figs. 1, 2 and 4). Carried upon the upper end of rod 30 is a block 31, said block carrying a horizontally disposed shaft 32 provided with a roller 33. The rod 30 is kept from rotation in its support in the machine frame by suitable means, such as a slot 34 cut longitudinally in the rod 30. Into the slot 34 projects a pin 35 formed at the inner end of a screw 36, which screw is threaded into the support 2. The rod 30 thus may move longitudinally while it is held against rotational movement. A spring 27 conveniently coiled about the rod 30 is in compression between the under side of the extended portion of the frame 2 and a washer 28 held on the lower end of rod 30 by a pin 29. Rod 30 is thus held retracted, as shown in Fig. 4, with roller 33 in position to guide the film strip while it is running.

Means are provided for limiting or determining the upward and downward movement of rod 30, and of the roller 33, and also for determining the extent of movement of the roller 33, thereby controlling the length or extent of the reserve loop established in the film strip. In the embodied form of

such means, a spring-pressed pin 38 operates in an aperture 39 in the upper enlarged part of the frame 2, the pin 38 being acted upon by spring 40, the pressure of spring 40 being regulated by a screw 41. Formed in 70 the rod 30 is a notch or recess 42 into which the pin 38 is projected by the spring pressure to limit the upward travel of the rod 30. Beneath the block 31 there is provided a screw or screws 43 threaded into the upper 75 surface of the frame piece 2. The screw 43 may be turned up or down to determine the lowest point of travel of the block 31 and roller 33. Thus the extent of travel of the roller 33 and of the reserve loop or film are 80 regulated and determined, and the roller 33 is movable between the position shown in Fig. 1 and that shown in Figs. 2 and 4, in its upper position forming the reserve loop in the strip preparatory to running it 85 through the machine, and in the lower position guiding the strip while it is being run and projected.

It will be understood that when the film is being threaded through the machine preparatory to starting it into operation, roller 20 and roller 33 are in the position shown in Fig. 1, and after the film strip is threaded through the machine, these rollers are moved to the position shown in Figs. 2 and 95 4. When in the latter position, the roller 33 coöperates with the curved plate 44, to guide the film in the rear of the lens carried in tube 4. The end of shaft 32 extends outwardly, to the right in Fig. 3, to serve as a 100 hold for the hand in moving the roller 33 up or down. The mechanism for establishing the film loop is entirely at the rear, and there is no construction at either side to interfere with the hands of the operator, and the mechanism is firmly mounted upon the machine frame and in a position directly above its supporting and guiding means.

Any suitable or approved form of devices may be provided for guiding the film strip 110 past the rear end of the lens 4, and for properly "framing" the picture for projection, and in the drawings herewith said devices are shown of the same general form as in my Patent No. 1,280,676 and need not be 115 described in detail.

After the film strip α has passed the projecting position, it passes over a sprocket roller 50, which is intermittently moved. My suitable mechanism, such for instance as is shown and described in my Patent No. 1,280,676 already referred to is shown in part in the drawings herewith. Coöperating with the sprocket wheel 50 is a roller or disk 51 carried upon an arm 52 pivotally 125 mounted on shouldered screw 49 which is mounted in a bracket 53. The arm 52 has angularly disposed surfaces 54 coating with a flat spring 55, to hold the arm 52 and roller 51 in either the open or closed posi- 130

tion, that is the position in which the film strip is threaded through (Fig. 1) or the position in which the strip is run during projection (Fig. 2). The screw 56 and co-
5 operating devices are part of the picture framing mechanism adjustments shown and described in my said prior application.

In the embodied form of reciprocable or sliding device for establishing a reserve 10 loop in the film strip between the intermittent feed and the rewinding reel, there is comprised a longitudinally slidable rod 60 mounted in brackets or bearings 61 and 62 carried upon the frame plate 1. Said rod 15 60 is kept from rotational movement by suitable means, the illustrated embodiment comprising a slot 63 cut longitudinally in the pin 60, into which slot projects a pin 64 formed at the inner end of a screw 65, 20 which screw is threaded into the bracket 62.

Mounted upon the rod 60 and secured thereto in a suitable manner, as by a pin 66, is a block 67. Mounted upon block 67 is a shaft 68 carrying a roller 69. Roller 69 25 when in depressed position acts to keep the film strip on the sprocket teeth of roller 80, the roller 69 being circumferentially grooved for this purpose. The upward movement of rod 60 and of roller 69, referring to Fig. 5, 30 is limited by suitable means such as a spring detent 70 mounted in an aperture in the bracket 61, and spring-pressed by spring 71, a screw 72 serving to regulate the pressure of the spring 71. A notch or depression 73 35 in the rod 60 co-operates with the spring detent 70. The downward movement of the rod 60 and the roller 69 is nicely and accurately regulated by a screw 74 threaded into the base 3 of the machine frame, this mecha- 40 nism also serving to regulate the pressure between roller 69 and strip feeding roller 80. A spring 75 is coiled about rod 60 and is in compression between bracket 61 and arm 67 and presses roller 69 to its lower limit. The 45 end of shaft 68 may be extended outwardly, as shown at the right hand end in Fig. 3, to serve as a handle to raise or lower roller 69.

The film strip is threaded about the intermittently moving sprocket roller 50, thence 50 over the roller 69 (when in the position shown in Fig. 1) and from there the strip is passed about the continuously rotating sprocket roller 80. The film strip thence passes over the guiding and supporting 55 roller 81 and is wound upon the reel 82, which is carried upon shaft 83. When roller 69 is moved from the position of Fig. 1 to the position of Fig. 2, the reserve loop is established and is maintained between the 60 continuously unwinding reel and the intermittent feed past the lens during the feed of the film strip.

Reel 82 is driven in a suitable manner, as by a belt 84. The belt 84 runs over a 65 pulley 86 upon the shaft 85 of sprocket

roller 80 and over a pulley 87 on shaft 83. There is a friction drive between pulley 87 and reel 82, operating in a known manner. The pulleys are so proportioned that the belt will slip upon the reel pulley, the continuously rotating sprocket wheel 80 regulating the rate of winding of the film strip irrespective of the amount of film upon the reel, in a well-known manner.

70 The words continuously or constantly running as applied to certain rollers and mechanisms will be understood as being used to differentiate from the intermittently operating mechanism for moving the central portion of the film strip between the successive 80 projections of the series of pictures.

Suitable driving connection for all the mechanism will be provided, a portion of which is shown at the left in Fig. 3, and which need not be described herein in detail.

85 It will be understood that departures may be made from the precise constructions shown and described within the scope of the appended claims, without departing from the principles of the invention, and without sacrificing its main functions and advantages.

90 What I claim as my invention and desire to secure by Letters Patent is:—

1. A motion picture machine including in combination picture projecting means, means 95 for guiding the film past the projecting means, film feeding means including devices for intermittently feeding the film, and means for forming a reserve film loop at one side of the projecting means and comprising 100 a longitudinally slidable rod and a film engaging roller mounted thereon, said roller in one position of said rod forming part of the film feeding means.

105 2. A motion picture machine including in combination picture projecting means, film feeding means including devices for guiding the film past the projecting means, means for intermittently feeding the film, and means manually operable for forming a 110 reserve film loop at one side of the projecting means and comprising a longitudinally slid- 115 able rod and a film engaging roller mounted thereon, and means for limiting the movement of said rod in both directions.

3. A moving picture machine including in combination two film feeding sprockets spaced apart from each other, a film engaging roller and a rod on which said roller is mounted, said rod being manually longitudinally slid- 120 able to establish and measure a reserve loop of film between the two sprockets, while the film is being threaded through the machine.

125 4. In a motion picture machine, a film engaging member and a carrier therefor mounted to move to and fro longitudinally relatively to the film path and adapted to be controlled so as to be moved positively into either one of two positions, said member 130

- in one of its positions engaging the film as a presser roller and in the other position adapted to have the film passed about it thereby to form a loop in the film.
5. In a motion picture machine a reserve loop establishing device including a solely manually longitudinally slidable rod, a film engaging roller mounted on said rod, and means for regulating the amount of travel 10 of said rod and roller, and a spring impelling said rod in one direction.
6. In a motion picture machine a reserve loop establishing device including a solely manually longitudinally slidable rod, a film
- engaging roller mounted on said rod, and 15 means for regulating the amount of travel of said rod and roller, a spring impelling said rod in one direction, and a detent for holding the rod against the action of the spring. 20
- In testimony whereof, I have signed my name to this specification, in the presence of two subscribing witnesses.

JOHN DARBY.
